FLEXIBLE POCKET RECEPACLE

Robert E. Dingman, Indiana, Pa.

Application July 21, 1944, Serial No. 545,932

2 Claims. (Cl. 150—36)

1

This invention relates to an improved flexible pocket receptacle or wallet adapted to contain bills, papers, letters, cards, stamps and the like.

An object of the invention is to provide in such a wallet or receptacle an out-of-sight or secret pocket of new and particularly advantageous construction to receive and contain bills of large denomination and valuable papers so formed that when the wallet is spread open neither the contents of said pocket nor the pocket itself is visible.

Heretofore in wallets having pockets intended to be concealed, the inner members or walls of such pockets have lain completely within the wallet and entirely under some other layer of material. Because of their wholly interior position, such members or walls have of necessity been made of an extremely soft, pliable material or leather different from the more rigid material or leather of the main members or walls. Such use of material different from that of the wallet proper has defeated the end sought because its presence is easily detected and makes obvious an additional compartment. Also, when papers and bills are placed under a soft wall, their bulk is readily seen and felt through the material.

An object of this invention is to provide in a wallet a secret pocket of such construction that the inner member, wall or panel is partially exposed when the wallet is unfolded to normal open position and which construction permits the use of the same, more rigid, material of which the other members of the wallet are made. Thus the defects mentioned above are eliminated, the pocket is rendered completely unobvious, effectively concealed, and its contents, because of the semi-rigidity of the material, cannot be detected through it.

Another object is to provide such a secret pocket without adding substantially to the bulk of the wallet.

An additional object is to provide a secret pocket construction that puts to more effective use the material and space that has hitherto been used in wallets for purposes of lining the outer or back wall thereof.

Another object is to provide such a secret pocket which can be unobviously made to open automatically and become instantly and easily accessible for the insertion or withdrawal of bills and papers.

Other objects of the invention will appear from the following description, reference being made to the accompanying drawing in which

2

Figure 1 is an inner or front side elevation showing the wallet in open position with the secret pocket closed;

Fig. 2 is a cross-sectional view on the line 2—2 of Fig. 1;

Fig. 3 is a cross-sectional view on the line 3—3 of Fig. 1;

Fig. 4 is a perspective view showing the wallet with the secret pocket open and exposed; and

Fig. 5 is a cross-sectional view on the line 5—5 of Fig. 1.

The wallet as shown in Figs. 1 to 5 inclusive is composed of flexible and resilient material such as semi-rigid billfold leather and comprises an outer rectangularly-shaped wall 10 which is foldable on a vertical line midway between the ends. The margin of wall 10 is skived to provide a narrow portion which is folded inward all around as shown at 11.

Against the inner side of wall 10 and under its folded-over edge 11 two separate rectangularly-shaped end members 12 and 13 are laid with their outer edges even with the lines of folds respectively on the end edges of wall 10 and their lower edges even with line of fold on the lower edge of wall 10. The upper edge of member 12 lies along the line of fold on the upper edge of wall 10 but about one-third of the distance from its outer end, the upper edge of member 12 is turned backward and adhesively secured upon said member for about a quarter of an inch so that the greater part of said upper edge is not included within folded-over edge 11. The inner edge of member 12 is similarly folded backward and adhesively secured upon said member to give a neat finished edge. Member 12, therefore, has a free unbound inner corner and side which may be lifted and bent back. The upper edge of member 13 coincides with the line of fold on the upper edge of wall 10, while the inner edge of said member is turned back and adhesively secured as with member 12.

As shown, additional exposed pockets may be provided by superposing member 14 on member 12, member 15 on member 13, and member 16 on member 15, all under the folded-over edge 11. The outer and lower edges of member 14 lie along the lines of fold on the outer and lower edges respectively of wall 10. Member 14 may be shaped as shown narrower at the top than at the bottom, with its upper and inner edges slight distances short of the corresponding edges of member 12. The upper, sloping and inner edges of member 14 are turned backward and adhesively secured on said member.

Member 15 is shaped similarly to member 13 and of the same width but shorter. Its upper, outer and lower edges coincide with the lines of fold on the corresponding edges of wall 10 but its inner edge is turned backward and adhesively secured. A line of stitching 16 secures member 15 to member 13 so that two compartments, the upper wider than the lower, will be formed. A rectangular opening may be cut in the upper part of member 15 and transparent material adhesively secured to the reverse side of the frame thus made to provide a window 17 for identification card, etc. The lower of the compartments is designed to be used for personal and business cards; and, because its opening faces the line of fold of the wallet, rather than in any other direction, the cards are securely locked in without any danger of slipping out when the wallet is folded.

Member 18 is shaped as shown with its outer and lower edges coinciding with lines of fold on the outer and lower edges respectively of wall 10. The inner edge of member 18 is skived and turned over the inner edge of member 15 and stitched as shown.

The out-of-sight or secret pocket is formed by means of member 19 which is a panel of the same flexible, resilient material such as semi-rigid bill-fold leather as the other members and which is superposed on wall 10 and lies for part of its length under member 13. The outer edge of member 19 lies along the line of fold on the outer edge of wall 10. The upper and lower edges of member 19 lie along the lines of fold on the upper and lower edges of wall 10 as far inward as the turned inner edge of member 13. Member 19 crosses the portion of wall 10 exposed between members 12 and 13 and is foldable on a vertical line to correspond with the line of fold of said wall 10. From the turned inner edge of member 13 inward, no part of member 19 is included within turned-over edge 11 on wall 10, and from that point on the upper and lower edges of member 19 extend merely up to the said turned-in edge 11 on wall 10. The inner portion of member 19 is inserted between wall 10 and member 12 and is shaped as shown, being wider at the top than at the bottom with the upper corner rounded off and its inner edge sloping to the center of wall 10. The sloped inner edge of member 19 is accurately designed so that its curvature precisely coincides with the curve formed at the bend of member 12 when the free inner corner of that member is lifted and bent back. The innermost extremity of member 19 reaches no further than the point at which the free part of the upper edge of member 12 terminates.

It will be seen that, since the inner portion of member, wall or panel 19 which conceals the mouth of the secret pocket has a flap formation precisely shaped, as above described, and is freely insertable between wall 10 and especially constructed member 12, and, since the closure over the mouth of the secret pocket is exposed at the interval between the members 12 and 13; that is, has no overlying layer of material where the fold of the wallet occurs, it is possible to make the wall or panel 19, comprising the inner wall of the secret pocket and forming the closure thereof of the same material as the other members of the wallet.

The several members having been positioned on wall 10 as indicated, the skived edge 11 of said wall 10 is folded around and over the ad-

jacent edges or adjacent parts of edges of members 12, 13, 14, 15, 18 and 19 and in the interval between the edges of members 12 and 13 over on wall 10 itself and stitched. Since, as noted, from the inner turned edge of member 13 inward, no part of member 19 is within turned-over edge 11 on wall 10 and thus not included in the stitching, the inward part of member 19 is left as a free unbound flap.

As a result of the edge stitching, pockets or compartments are formed between wall 10 and member 12; member 12 and member 14; wall 10 and member 19; member 19 and member 13; member 13 and the upper part of member 15; member 13 and the lower part of member 15; member 15 and member 18.

When the wallet is opened up in normal position and its inner or front surfaces exposed, the existence of the pocket formed between wall 10 and the rectangular bound-in portion of panel 19 is not apparent. This, as will be seen, is because the opening of said pocket is completely hidden by panel 19 whose true function is concealed because it is visible at the interval between members 12 and 13 and because it is made of the same material as the rest of the wallet. Furthermore, panel 19 appears to be nothing more than a facing for or part of outer wall 10, since its upper and lower edges, unlike any other edge, are not finished or turned and lie along the respective turned-over and finished edges 11 of outer wall 10, and additionally because at the said interval panel 19 has a vertical line of fold corresponding exactly to the line of fold of outer wall 10.

The improved construction of the wallet affords an additional advantage in that the secret pocket can be made to operate automatically and access gained thereto by simple but unobvious manipulation of the wallet. Thus, when it is desired to insert bills of large denomination or valuable papers therein, it is necessary only to open the wallet to the open position shown in Fig. 1, then to bend the wallet back on itself, holding the thumb tight against the inner left side which holds the inner free portion or free flap of member 19 in place. Upon release of the thumb, the said flap portion of member 19 springs out of position exposing the opening to the secret pocket and rendering it accessible. To close the secret pocket, it is necessary only to lift the free end of member 12 and insert the free flap portion of member 19 thereunder so that it returns to its normal position and completely closes and conceals the secret pocket. Because the inner sloping edge of member 19 is accurately curved to precisely coincide with the curve formed at the bend of member 12, there is no undue distortion or buckling of the semi-rigid bill fold leather of members 19, 10 or 12.

The features of the wallet's construction which result in the automatic operability of the secret pocket are the following: The secure binding in of panel or member 19 for over half of its length to the beginning of the vertical fold; the free flap formation of the remainder of member 19; the shape of the inner or flap portion of member 19, tapering down from top to bottom with the accurate curvature of its inner edge; the coincidence of the vertical fold of said flap with the vertical median fold of wall 10; the limitation of the insertion between wall 10 and member 12 of said flap, even at its longest, to a distance not greater than two-thirds of the width of member 12, that is to a point short of where the upper

edge of member 12 is bound in by the turned-over edge 11 of wall 10, and the said flap at its shortest, to a point just under the inner edge of member 12; and the free upper inner corner of member 12.

Thus when the wallet is bent backward and held as above described, the greater fixed portion of member 19 tends to draw its lesser free flap portion with it and the exposed part of said flap is arched upward in a direction opposite to its normal downward vertical fold. As a result, great tension is built up and when the thumb is released, since the flap is not fastened along the vertical line of fold and since the flap is not inserted far enough into the compartment between wall 10 and member 12 to permit a downward counter-stress on the free flap within the compartment, the said flap springs suddenly upward out of said compartment.

While the invention has been disclosed herein, in an embodiment at present preferred, for illustrative purposes it is obvious that changes in construction, form and arrangement of parts may be made without departing from the scope of the invention. I, therefore, do not wish to be limited to the precise details of construction set forth, but desire to avail myself of such variations and modifications as come within the scope of the appended claims.

I claim:

1. A flexible pocket receptacle comprising an outer wall member having turned-over margins and foldable vertically on a median line, a pocket wall member secured to said outer wall on one side of said median line with its outer, lower and part of its upper edges under said margins to form an inwardly and partially upwardly open

pocket and a flexible and resilient member, foldable coincidentally with said outer wall member, having its outer portion secured to said outer wall member on the other side of said median line

5 with its outer and parts of its lower and upper edges under said margins to form an inwardly open pocket and having its inner unsecured portion extend across the space between the two pockets and into the first pocket for a distance not more than two-thirds of the length of said first pocket, the said unsecured inner portion being longer at the top than at the bottom and its free inner edge sloping progressively downwardly and inwardly from top to bottom toward its vertical line of fold to a point just under the inner lower corner of the first pocket.

2. A flexible pocket receptacle comprising an outer wall member foldable vertically on a median line, a pocket wall member secured to said outer wall on one side of said median line to form an inwardly and partially upwardly open pocket and a flexible and resilient member, foldable coincidentally with said outer wall member, having its outer portion secured to said outer wall member on the other side of said median line to form an inwardly open pocket and having its inner unsecured portion extending across the space between the two pockets and into the first pocket, the said unsecured inner portion being longer at the top than at the bottom and its free inner edge convexly curving progressively downwardly and inwardly from top to bottom toward its vertical line of fold from a point adjacent the outward termination of upwardly open portion of the first pocket to a point adjacent the inner lower corner of the first pocket.

ROBERT E. DINGMAN.
